J. H. Harness
ATTORNEY.

UNITED STATES PATENT OFFICE.

JOSEPH GALAMB, OF DETROIT, MICHIGAN, ASSIGNOR TO FORD MOTOR COMPANY, OF HIGHLAND PARK, MICHIGAN, A CORPORATION OF DELAWARE.

TIMER FOR IGNITION SYSTEMS FOR INTERNAL-COMBUSTION ENGINES.

Application filed December 20, 1920. Serial No. 431,987.

To all whom it may concern:

Be it known that I, JOSEPH GALAMB, a citizen of the United States, residing in the city of Detroit, in the county of Wayne and

5 State of Michigan, have invented new and useful Improvements in Timers for Ignition Systems for Internal-Combustion Engines, of which the following is a specification.

The object of my invention is to provide 10 an improved timer for ignition systems for internal combustion engines of simple, durable, and inexpensive construction.

A further object of my invention is to provide a contact-making device to close the 15 circuit successively through the various spark plugs of an internal combustion engine and to so arrange the parts of this device that a maximum accuracy in timing may be secured together with a lasting construction.

A further object of my invention is to provide, in combination with the casing usually used in connection with commutators or timers, a ring having spaced insulated contacts therein and a roller to roll around the ring having a combined rolling and wiping contact with the ring.

A further object of my invention is to provide, in connection with such a structure, 30 a roller having flanges at either end adapted to have a wiping action relative to the ring and to provide means for yieldingly holding these flanges into contact with the ring.

A further object of my invention is to 35 provide an improved segmental commutator roller having flanges on either segment, which are yieldingly forced in a direction to cause the flanges to engage side surfaces of the ring member.

40 A further object of my invention is to provide spherical or ball shaped contacting surfaces between the parts of the roller and the parts of the arm, whereby the pressure forcing the segments of the roller together may be applied centrally thereof, and 45 whereby there may be a relatively large wiping contact between the roller and arm when the former is revolving.

With these and other objects in view, my 50 invention consists in the arrangement, combination and construction of the various parts of my improved device, as described

in the specification, claimed in my claims, and shown in the accompanying drawings, in which:

55 Figure 1 is a vertical central sectional view taken on line 1—1 of Figure 2, and

Figure 2 is a similar view taken on the line 2—2 of Figure 1.

Referring to the accompanying drawings, 60 I have used the reference numeral 10 to indicate, generally, the camshaft of an internal combustion engine which extends through a supporting member 11. Mounted on this supporting member in any suitable 65 manner is the commutator housing 12, which is a hollow casing adapted to support an insulating ring 13. The ring 13 has set into its inner surface a plurality of contacts 14, which are each connected with a binding 70 post 15, the latter extending through the insulating ring and casing so that lead wires may be connected thereto. Mounted on the end of the shaft 10 within the casing 12 is a sleeve 16 which is held from movement laterally to the shaft by any suitable means, 75 as by a pin 17. Extending laterally from the sleeve 16, and preferably formed integral therewith, are a pair of spaced ears 18, having alined openings adjacent to their outer ends. Extended through the openings is a pintle 19 designed to form a pivot for the movable portion of the commutator arm. The commutator arm in the form here shown is composed of two spaced strips of resilient 80 material 20 which are pivotally supported intermediate of their ends on the pintle 19. One end of these members is connected by a rod 30 which serves to hold the members from movement relative to each other and 85 for another purpose which will be herein-after brought forth. At the opposite end of the members 20 a pin 21 extends between them to form a pivotal support for the commutator roller. The pin 21 has contracted 90 end portions 22 upon which are mounted washers 23, which are dished and provided with a central opening to receive the contracted portion 22.

The contracted end portions 22 are of 100 such length that the adjacent portions of the ends 20 may move somewhat thereon, whereby the members 20 may bend somewhat if any pressure is exerted against them

without throwing the pin 21 out of parallel with the shaft 10. The extensions 22 have flattened sides 22* which co-act with corresponding portions of the washers 23 to hold the pin and washers from rotation relative to the members 20.

Mounted on the pin 21 between the washers 23 is the commutator roller which comprises two segments 24 and 25. Each of these segments have at their outside edges a laterally extending flange 26 designed to engage the side surfaces and inner edges of the commutator ring.

The roller segments have their outer faces recessed to correspond to the curvature of the washers 23. Encircling the pindle 19 are the coils of the spring indicated by the dotted lines 27 in Figure 2, one arm of this spring being extended to position to engage the rod 30 and the other arm being extended to position to engage the surface of the sleeve 16. This spring is so arranged that it tends to throw the rod 30 toward the shaft 10 and the roller away from this shaft, thereby yieldingly forcing the roller into contact with the ring 13.

In this connection it will be noted that the spring 27 is so coiled that the ends thereof which contact with the pin 30 and sleeve 16 extend from the underside of the pindle 19, that is, they extend from the side closest to the sleeve 16. By this construction it will be seen that any movement of the roller away from the ring 13 will tend to further wind the coiled portion of the spring around the pindle 19 so that the spring 27 resists any tendency for the roller to be thrown away from the ring not only by the winding up of the coil but also by the resistance of the portion of the spring adjacent to the pindle to the bending of the spring caused by such further winding. This mounting of the spring, therefore, gives a maximum force to urge the roller against the ring with a minimum weight of spring. I have provided a groove 29 at approximately the center of the inner face of the ring 13 in order to obviate any danger of the unequal wearing of the ring at the meeting edges of the segments 24 and 25 of the roller.

In the practical operation of my improved device it will be understood that the shaft 10 is a portion of the camshaft of an internal combustion engine, and that the binding posts 15 are so connected with the ignition system of the engine that when the circuit is closed through one of the binding posts, a spark may be caused at a corresponding spark plug. It will also be understood that the circuits are closed by grounding through the roller, arm, shaft and its connections, so that the circuit is completed as soon as this grounding takes place.

From the foregoing description it will be seen that rotation of the shaft 10 will cause

the roller to roll around the ring thereby successively grounding the binding posts and closing the corresponding circuits.

The resiliency of the members 20 is such that when for any reason the ring 13 might tend to separate segments 24 and 25, then that these members may give sufficiently to permit the necessary spreading of these segments. If the shaft 10 or the casing 12 should for any reason move axially resiliency of these members 20 will also permit the axis of the roller to remain substantially parallel with the axis of the shaft 10, and at the same time prevent binding between the flanges 26 and the ring 13. The width of the ring 13 and contacts 14 is such that the segments 24 and 25 of the contact roller are normally slightly spaced apart so that the resiliency of the members 20 tends to throw the two segments together, thereby yieldingly holding the flanges 26 into engagement with the sides of the ring and contacts. In case the ring and contacts wear down sufficiently the segments will of course meet, but even in this situation the roller will retain all of the advantages of the commonly used one piece roller. The roller segments themselves are specially hardened so the wear thereon is very slight. The dished washers 23, together with the recessed faces of the roller segments, space the arms 20 from the segments so that the contacting surfaces are always adjacent to the axis of the roller whereby the roller will rotate even though the segments thereof may meet due to wear on the commutator parts. This structure also gives a wiping contact between the roller segments and the washers of considerable area as the washers are held from rotation by the engagement of the flat sides of the openings therethrough with the flat sides of the contracted portions 22*, and the electrical connection between the arm and roller is the more perfect. The continuance of this wiping contact is insured by the yielding pressure of the arms 20.

During the progress of the roller around the ring it will be seen that the flanges 26 will engage the side surfaces of the ring and contacts therein and will have a wiping contact with such portions in addition to the rolling contact of the central portion of the roller. This wiping contact feature is of very great importance as neither a rolling or wiping contact, used independently of each other, have heretofore operated as efficiently as I find that the combined contacts operate.

The arms 20 have sufficient resiliency so that they may be separated far enough adjacent to the roller to permit the pin 21, the washers 23, or the roller segments 24 and 25 to be removed for inspection or replacement, whereby the roller may be changed without replacing the arm assembly. The

resilient arms 20 therefore permit the roller segments to sway laterally, force the segments together, and permit the roller to be changed in addition to performing the usual functions of a commutator arm. The dished washers insure uniform bearing surfaces under all working conditions and improve the electrical connections.

Some changes may be made in the arrangement and construction of the various parts of my improved device without departing from the spirit of the invention therin, and it is my intention to cover by my claims such changes as may be reasonably included within the scope thereof.

I claim as my invention:

1. In a commutator structure, a pair of spaced resilient arms, a pin extended therebetween, dished washers on the pin between the arms, means for holding the pin and washers from rotation relative to the arms, and a two part roller mounted between the washers.

2. In a commutator structure, a pair of spaced resilient arms having aligned open-

ings of irregular shape at one end, a pin extended between said ends having contracted end portions shaped to enter and fit said openings, dished washers having similar openings mounted on the contracted portions between the arms, and a two part roller mounted on the pin between the washers, the outer surfaces thereof being recessed to correspond to the dishing of the washers.

3. In a commutator structure, a commutator casing having an insulating ring therein having contacts of conducting material inserted into said ring at intervals, said ring and contacts having a longitudinal central groove in their inner face, a shaft extended into said casing, a roller carried by said shaft and yieldingly urged into contact with said ring and contacts, said roller being composed of two sections and having means associated therewith for yieldingly urging said sections toward each other.

JOSEPH GALAMB.

Witness:

E. L. DAVIS.
